UNITED STATES PATENT OFFICE.

BERNHARD ZWILLINGER, DECEASED, BY KLARA ZWILLINGER, ADMINISTRATRIX, OF NEW YORK, N. Y., ASSIGNOR, BY MESNE ASSIGNMENTS, TO TAR & PETROLEUM PROCESS COMPANY, OF CHICAGO, ILLINOIS, A CORPORATION OF ILLINOIS.

METHOD OF DISTILLING COAL.

Application filed July 14, 1922. Serial No. 574,936.

In modern coke oven practice for the production of metallurgical coke and by-products great efforts have been made in the last decades to carbonize large masses of coal and produce a uniformly carbonized coke with as small an amount of heating gas as possible.

In spite of the progress which has been achieved in some directions, a considerable number of serious defects and disadvantages occur.

The coking of large masses in high, narrow, long chambers has first of all led to considerable complication in the construction and a large consumption of materials and labor.

In addition to these economic disadvantages the modern by-product oven has other drawbacks which limit its use to the carbonization of certain sorts of coals or mixtures of coals. Such coals for instance which expand during the degasifying process can only be used when mixed in certain proportions with a shrinking coal; otherwise the wear and tear would be too large and the carbonization might even lead to destruction of the ovens.

Furthermore it is impossible to obtain all the valuable by-products in an unimpaired state, because the coal shrinks away from the heating walls whereby between the coke ends and walls irregular gaps and crevices are formed which serve as paths for the travel of the gases issuing from the coal. The crude gases being subjected to the catalytic influence of highly heated brick walls having an area of about 720 square feet and of the incandescent coke ends, it can be readily understood that a part of the by-products must be destroyed. The formation of these gaps and crevices between the heating walls and the coke ends is the cause of other serious defects in addition to the loss of valuable by-products. Owing to the irregularity of the gaps it is impossible to apply the heat in such a manner so as to produce a uniformly carbonized coke which is of so great importance in blast furnace operation—regardless of what method of heating is applied to these high ovens and

of what nature the means are for controlling the heat. The problem of heating the charge becomes still more complex and difficult for the following reasons:

The crude gases issuing from the charge as the carbonization progresses towards the center are considerably lower in temperature than the source of heat, i. e. the heating wall, and since the gases travel from the center towards the walls, they will take up a certain amount of heat from the wall. This retards the progress of heat to the core of the charge. The gases will escape in a superheated condition to the dome of the oven and to the tar main. The flow of gases takes place on a counter current principle, the gases being generated inside the coal charge at one temperature and flowing towards the source of heat—the heating wall—with a zone of higher temperature. This is disadvantageous to the intended purpose of transferring the heat from the walls to the coal charge. If one considers that the gases represent about 25% more or less of the entire weight of the coal the retarding action these gases exert upon the heat transfer must be large, and as a consequence this also prolongs the coking time. It also necessitates larger condensing surfaces in the condenser of the by-product plant to cool off the higher temperatures due to the fact that the gases leave the oven in a highly heated state. Moreover the resulting decomposition of the gases results in an endothermic reaction which absorbs heat from the heating wall. Still another difficulty in the equal distribution of heat thru the heating walls is due to the taper. The width of the charge on the pusher side being smaller than on the opposite end of the oven, it will take less time to finish that part of the charge with the result of producing an over or under carbonized coke product.

The irregularities which arise during the distillation process by the behavior of the charge in the high, narrow by-product oven, are uncontrollable, and for this reason the modern by-product oven fails to achieve its most important purpose, i. e. the distribution of the heat in such a manner as to car-

bonize the coal charge uniformly. The heat application is far from being accurate.

The great significance of the by-product oven as an industrial factor justifies a detailed explanation of the aforesaid defects, and will also assist in understanding my novel process of carbonizing coal, which eliminates the described disadvantages.

My invention is illustrated in the accompanying drawings in which the illustrations show one or more ways for carrying the invention into effect.

Fig. 1 is a longitudinal section on line 1—1 of Fig. 2.

Fig. 2 is a vertical cross section on line D—D of Fig. 1.

Fig. 3 is a vertical section and Fig. 4 is a horizontal section of a modification.

As shown best in Figs. 1 and 2, the heating floor or sole 1 of the oven chamber, sealed from the admission of air, is of considerable width and crowned by a low arch 2 which is provided with a number of charging holes 3 for filling the oven with the material to be coked. The charge to be coked or distilled is heated underneath and the heat supplied from both ends of the charge. The charge consists of a flat, elongated, horizontal layer of coal which is longer than its breadth, thus providing opposite ends for the layer at each end of the longitudinal axis of the charge.

In the best embodiment of carrying out the method, short narrow longitudinal, independent heating flames are provided, each extending along the sole of the oven and supplying coking heat at a temperature sufficient to coke the charge. The heat supply is subdivided both lengthwise and transversely of the layer. Lengthwise a plurality of parallel, equal heating zones are utilized and these are in turn subdivided into groups by a transverse division wall. The combustion flues 4, 5 are divided by walls 6 forming channels 7, 8 which connect with waste gas main 9, 10. Each combustion flue is provided with a gas supply nozzle 11 which connects by pipe 12 with return gas main 13. Two series of gas supply nozzles are utilized, one for each oven front. The air for supporting the combustion is led to air chamber 14, 15, where it is exposed to the radiant heat of the waste mains 9, 10. An aperture in the arc of the upper air chamber connects by short vertical passages 16, in which air shut-off valve 16^a is located, to air super-heating channel 17, which runs along underneath the combustion flues 4, 5 thereby highly preheating the air which escapes by a number of holes 18 impinging on the gas from nozzles substantially at right angles whereby an intimate gas mixture and a complete combustion is produced, at a temperature sufficient to coke the coal. The oven is also equipped on both sides with combustion flues 19, 20, which are provided also at both

fronts of the oven with gas nozzles 21. These side combustion flues may or may not be used, as desired. The air is supplied to the side flues in a similar manner as for burning the gases in the sole flues.

The side wall flues are low—their height is more or less determined by the thickness of the coal layer which need not exceed 14 to 15 inches. It is obvious that in a sole coke oven having a width as from 5 to 12 feet, the heat from the side walls cannot have any influence on the coal layer located in the middle of the oven; in fact the introduction of heating the sides of the charge is in

the main to prevent any losses of heat from the sole flues which would occur, if the sole oven would have no side wall heating flues.

On the other hand the temperature in the side walls need never to exceed 900 to 1000 degrees centigrade and at times may be kept lower. In the sole combustion flues the temperature of the coking heat should not fall below 1250 degrees centigrade. It can be readily understood that if in the side wall flues and in the sole flues located next to the

side wall flues a temperature of 1250 degrees centigrade is maintained, narrow strips of coal running along the sides of the oven chamber, being subjected from two sides to the influence of heat, would be prematurely carbonized, while the balance of coal would be still in process. Such an occurrence is avoided by keeping the temperature in the side wall combustion flues at about 900 to 1000 degrees centigrade. Each of the flues is supplied with gas and air. The regulating means 22, 23 are easily accessible, and exposed to daylight.

By the division wall 6, which also helps to form the waste gas channels 7, 8 for burned gases, the flue system is divided into two equal halves, and as the oven is heated from both fronts the paths of travel for the combustible gas is very short. It also will be noticed that the entire area of the sole is subjected to the heat of combustible gases,

which is a considerable advantage over such methods, where the heat is applied to heating walls partly with combustible gases and partly with gases from which the greater part of the heat has been previously absorbed.

The operation of the oven is as follows:

After the oven is properly heated the covers 24 of the charging holes are taken off and the lorries moving on rails 25 discharge the coal into the oven. The doors 26 are then removed and the charge is leveled.

After leveling the charge the coal may be compressed by rolling cast iron rollers over the charge, in order to obtain a more dense coal, if so desired. The doors are replaced and luted so as to prevent the admission of atmospheric air. The gas nozzles 11 and air valve 16^a being opened, combustion takes

place in all the flues and the products of distillation issued from the charge escape thru ascending pipe 27 connected with a tar main (not shown) and are led to the condensation plant and worked up in the usual manner. As shown in Fig. 2 by arrows, the direction of the distillation gases in my sole coke oven escape always thru the cooler portion of the charge and not on the sides. The formation of gaps parallel to the oven floor in Fig. 2 is impossible, for the weight of the charge (which weighs from 5 to 8 tons) will press solidly upon the sole walls and the gases will escape in the direction indicated by arrows in Fig. 2.

The advantages of carbonizing the charge uniformly by my method will be apparent:

(1) The distillation gases are uniformly generated over all parts of the oven floor, due to the heating from both ends, and are conducted thru the cooler zones of the charge, thereby avoiding decomposition of the gases.

(2) With the elimination of the gaps parallel to the oven floor, the heat conduction is continuous and uninterrupted, and the hot gases will give up heat to the coal layer above. So the flow of gases has the same direction as the heat and is not counteracting its effect.

(3) The method of carbonizing coal avoids the disadvantage of the loss of heat subtracted from the heating wall by the gases traveling along them as in prior ovens in which high, narrow, horizontal, long chambers are used to receive the charge of coal.

(4) Having eliminated all the unknown factors which arise during the distillation in the high, narrow, chambers, the control and distribution of heat is more uniform and positive in my sole coke oven and by the better utilization of heat, the time for carbonization is reduced.

As previously stated, the charge of coal, subjected to my process, owing to its considerable width and to the comparatively shallow coal layer, may be compressed very effectively, as by means of a movable roller

which is to be applied on the top of the charge for the production of a dense coke. 50

What I claimed as new and desire to secure by Letters Patent is:

1. The method of distilling a flat, elongated, horizontal layer of coal which is thinner than its width and length, while the 55 coal is in a sealed oven chamber, which comprises subjecting the layer to coking heat from beneath from a plurality of parallel, longitudinal, independently regulable flames, air and gas for the flames being supplied 60 from opposite ends of the layer, and collecting the distillates so formed.

2. The method of carbonizing a flat, elongated, horizontal layer of coal, while on the sole of a sealed oven chamber which comprises supplying coking heat to the layer from below at a temperature sufficient to coke the coal by means of a plurality of independent flames, said flames originating at opposite ends of the layer, and extending 70 along the sole of the oven.

3. The method of distilling coal while on the sole of a sealed oven chamber which comprises spreading a charge of coal in an elongated shallow layer, supplying coking 75 heat, through the bottom and at both ends of the charge sufficient to coke the coal simultaneously supplying coking heat through both sides of the charge, and collecting the distillate so formed. 80

4. The method of distilling coal while on the sole of a sealed oven chamber which comprises spreading a charge of coal in an elongated shallow layer, supplying coking heat from below and from both ends of the charge simultaneously supplying heat from both sides of the layer to the charge, both sides being at a lower temperature from that of the bottom supply, and collecting the 85 distillate so formed. 90

In testimony whereof, I have signed my name to this specification.
